US00D679206S

(12) **United States Design Patent** (10) **Patent No.:** **US D679,206 S**
Götz (45) **Date of Patent:** **** Apr. 2, 2013**

(54) **SENSOR CHIP FOR BIOCHEMICAL ANALYZERS**

(75) Inventor: **Ulrich Götz**, Bonn (DE)

(73) Assignee: **Saw Instruments GmbH**, Bonn (DE)

(**) Term: **14 Years**

(21) Appl. No.: **29/393,484**

(22) Filed: **Jun. 6, 2011**

(30) **Foreign Application Priority Data**

Dec. 6, 2010 (EP) 001789710

(51) **LOC (9) Cl.** **10-04**

(52) **U.S. Cl.** **D10/81**

(58) **Field of Classification Search** D10/81;
422/50, 502, 68.1, 82.05–82.09; 435/288.3,
435/283.1, 287.1, 287.3, 288.7, 7.1; 359/577,
359/580, 586, 589; 436/518, 524, 527

See application file for complete search history.

(57) **CLAIM**

The ornamental design for a sensor chip for biochemical analyzers, as shown and described.

DESCRIPTION

FIG. 1 is a top perspective view of a sensor chip; and,
FIG. 2 is a top plan view of the sensor chip in FIG. 1.

1 Claim, 2 Drawing Sheets
